CLAIM

(57) The ornamental design for a dispensing system, as shown and described.

DESCRIPTION

FIG. 1 is an isometric front, top and left side perspective view of the dispensing system showing our new design;

FIG. 2 is a front elevational view thereof;

FIG. 3 is a rear elevational view thereof;

FIG. 4 is a left side elevational view thereof, the right side elevational view being a mirror image of the left side;

FIG. 5 is a top plan view thereof; and,

FIG. 6 is a bottom plan view thereof.

The broken lines are included for the purpose of illustrating portions of the dispensing system that form no part of the claimed design.
